UNITED STATES PATENT OFFICE

THOMAS LUND, OF BEVERLY, MASSACHUSETTS, ASSIGNOR TO UNITED SHOE MANUFACTURING CORPORATION, OF PATERSON, NEW JERSEY, A CORPORATION OF NEW JERSEY

NAIL DISTRIBUTOR

Application filed December 31, 1929. Serial No. 417,776.

My invention relates to nail-distributors, being particularly concerned with the preventing of the escape of nails or like fastenings from a drum containing a mass from which delivery is to be made.

The nail-drum of a distributor is commonly closed at the outer or rear side during operation, but at the inner side has an opening through which extend two nail-conveyors one of these being the raceway-structure or washboard receiving nails from the drum and forwarding them to the discharge device, and the other the chute by which nails wasting from the raceway are returned to the drum to be again delivered. Some of the nails dropping from the drum-buckets upon which they are elevated for delivery to the raceway tend to be so deflected that they escape through the opening and fall upon the floor. To confine the nails to the desired paths within the supplying system is an object of my invention. This I accomplish by the provision of a guard-plate for the drum-opening, and in which is an opening or openings for one or more nail-conveyors, this plate being arranged in close proximity to the drum-wall about the opening therein and so mounted as to permit its adjustment toward and from the drum. By this means, the opening in the drum may be almost entirely closed, save where the nail-conveyors pass through it, the closure at the meeting plane of the drum-wall and guard-plate being perfected by the adjustment of the latter upon its mounting. To enable this to bring about conformity under varying structural and supporting conditions of the drum, the plate may have both bodily and angular adjustment. As herein illustrated, a compound adjustment is obtained by pivoting the guard-plate upon a pin which may be placed in different positions laterally and clamped. A retaining means in the form of a brace is preferably employed to aid in holding the guard-plate. However the plate is mounted, the efficacy of the closure may be increased by the use of a nail-deflecting flange extending into the drum about the surface with which said plate co-operates, and one or more auxiliary plates may be carried by the guard-plate over

a portion of a conveyor-opening therein, this auxiliary plate being variable in position.

The accompanying drawings show one of the several possible embodiments of my invention,

Fig. 1 being a broken side elevation of that portion of a nail-distributor of which my invention is a part;

Fig. 2, a transverse section on the line II—II of Fig. 1;

Fig. 3, a broken detail, partly in section and partly in elevation, of one of the drum-pivots; and

Fig. 4, an enlarged section on the line III—III of Fig. 2.

The general organization of the nail-distributor illustrated is that disclosed in Letters Patent of the United States No. 1,005,303, Pope, October 10, 1911. Of this there appear in the drawings portions of a frame 10, a washboard or a nail-way 12 oscillating thereon, and parallel horizontal spindles 14, 14 fixed in the frame and upon which rotate rolls 16, 16. These rolls have grooves 18 and surfaces 20 spaced from said grooves to support, by peripheral flanges 22, 22, the front head 24 and rear head 26 of a nail-drum 28. Gearing 29 rotates the rolls, which act frictionally to turn the drum. A mass of nails contained in this drum is elevated by buckets spaced about its interior but not illustrated in the drawings, and dropped upon the nail-way, which retains a portion of them while others fall to the bottom of the drum to be again elevated. In the forward travel of the nails down the nail-way to a discharge device such as that of Pope, some fall therefrom or waste into a chute 30, which directs them back to the supply in the drum. In this elevation, descent, advance and return of the nails, they tend to be deflected through the opening at the inner side of the drum, which permits the passage through the head 24 of the nail-way 12 and the chute 28. These nails, falling upon the floor, are usually swept up and thrown away, causing a substantial loss.

To prevent the wasting of nails in this manner, I close the greater part of the opening in the head 24 by a guard-plate 32. This

plate is shown as circular and adapted to be positioned in close proximity to a surface 34 lying substantially at right angles to the axis of rotation of the drum and surrounding the opening. Since the manner in which the nail-drum is supported and rotated and its commonly rather inexact construction render uncertain the location of the surface 34, a mounting is provided for the guard-plate which permits it to be positioned in approximate parallelism and in close proximity to the drum-surface. A suitable form of mounting is provided by spaced lugs 36, 36 projecting horizontally from near the bottom edge of the plate and cooperating with vertical lugs 38, 38 upon the frame. Screws 40, beneath the heads of which are washers 42, pass through openings 44 in the frame-lugs, these openings being of considerably greater diameter than the screws. The inner ends of these screws are threaded into the plate-lugs. This manner of connection allows the guard-plate to be swung upon the screws as pivot-pins to conform angularly to the surface 34 and also to be shifted in all directions in its own plane. An adjustment which is approximately universal is thus obtained. When the relation has thus been established which will most uniformly close the opening between the drum and plate so no nails can escape, the position of the plate is fixed by tightening the screws, thus drawing together the pairs of lugs 36, 38. To correspondingly retain the upper part of the plate at the edge opposite the pivotal mounting against displacement from its adjusted position, it is preferably joined by a diagonal brace 46 to the frame. To permit a single bracing member to be employed for all positions of the plate, the connections 48 and 50 between the brace and the frame and plate, respectively, may be of the slot-and-screw type. The slot of the connection 48 lies in a substantially horizontal plane and that of the connection 50 in a substantially vertical plane. By shifting one or the other of these, the brace may be adapted to all plate-adjustments. To more certainly prevent nails from entering the space between the guard-plate and drum-surface 34, I have shown a flange 52 formed integrally with the plate and surrounding all but the upper portion of the drum-opening. Nails falling toward the space will strike the flange and be deflected back into the drum.

In the guard-plate 32 are two openings, to receive, respectively, the nail-way 12 and the return-chute 30. Because of the movement of the plate for adjustment, and since the dimensions of the elements, especially the sheet-metal chute, are uncertain, I may provide one or more auxiliary plates for attachment to the guard-plate over the conveyor openings. These plates appear at 54, 54 as angular, to conform to two adjacent sides of

the conveyor with which they co-operate. They have openings 56 to receive attaching screws 58 of less diameter than the openings and threaded into the plate 32. By these connections, the plates 54 may be secured as close to the conveyors as is possible and still avoid interference. 70

It will be seen that, by this arrangement, all the openings in the delivery side of the distributor-drum are effectively protected 75 against the accidental discharge of nails and by means adaptable to widely varying conditions.

Having described my invention, what I claim as new and desire to secure by Letters 80 Patent of the United States is:

1. In a nail-distributor, the combination with a rotatable drum having an opening, of fastening-conveying means passing through the opening, a guard-plate for the opening co-operating with a wall of the drum and provided with an opening to receive the nail-conveying means, and a mounting for the guard-plate arranged to permit its adjustment toward and from the drum. 90

2. In a nail-distributor, the combination with a rotatable drum having an opening, of fastening-conveying means passing through the opening, a guard-plate for the opening co-operating with a wall of the drum and provided with an opening to receive the nail-conveying means, and a mounting for the guard-plate arranged to permit its angular adjustment. 95

3. In a nail-distributor, the combination with a rotatable drum having an opening, of fastening-conveying means passing through the opening, a guard-plate for the opening arranged in proximity to a wall of the drum and provided with an opening to receive the nail-conveying means, and a pivotal mounting for the guard-plate arranged to permit its bodily and angular adjustment. 100

4. In a nail-distributor, the combination with a rotatable drum having an opening, of fastening-conveying means passing through the opening, a guard-plate for the opening co-operating with a wall of the drum and provided with an opening to receive the nail-conveying means, a mounting for the guard-plate arranged to permit its adjustment toward and from the drum, and retaining means for the guard-plate adjustable to correspond to the adjustment of the mounting. 110

5. In a nail-distributor, the combination with a rotatable drum having an opening, of fastening-conveying means passing through the opening, a guard-plate for the opening co-operating with a wall of the drum and provided with an opening to receive the nail-conveying means, a mounting for the guard-plate arranged to permit its angular adjustment, and retaining means for the guard-plate variable in position to correspond to the angular adjustment. 120

6. In a nail-distributor, the combination with a rotatable drum having an opening, of fastening-conveying means passing through the opening, a guard-plate for the opening co-operating with a wall of the drum and provided with an opening to receive the nail-conveying means, a pivotal mounting for the guard-plate situated near one edge thereof and arranged to permit its bodily and angular adjustment, and retaining means for the guard-plate having variable engagement with a portion of the plate opposite the pivotal mounting.

7. In a nail-distributor, the combination with a rotatable drum having an opening, of fastening-conveying means passing through the opening, a guard-plate for the opening arranged in close proximity to a wall of the drum and provided with an opening to receive the nail-conveying means, a mounting for the guard-plate arranged to permit its adjustment toward and from the drum, and an auxiliary plate variable in position upon the guard-plate over its opening.

8. In a nail-distributor, the combination with a rotatable nail-drum having an opening and a surface lying in a plane substantially at right angles to the axis of the drum, nail-conveying means passing through the opening, a guard-plate provided with a surface arranged for co-operation with the drum-surface, a flange extending into the drum about the drum-opening and an opening to receive the nail-conveying means, and a mounting for the guard-plate arranged to permit the adjustment of its surface toward and from the drum-surface.

9. In a nail-distributor, the combination with a rotatable nail-drum having an opening and a surface lying in a plane substantially at right angles to the axis of the drum, nail-conveying means passing through the opening, a guard-plate provided with a surface arranged for co-operation with the drum-surface, a flange extending into the drum about the drum-opening and an opening to receive the nail-conveying means, a mounting for the guard-plate arranged to permit the adjustment of its surface toward and from the drum-surface, and an auxiliary plate variable in position upon the guard-plate over its opening.

10. In a nail-distributor, the combination with a rotatable nail-drum having an opening, a nail-conveyor passing through the opening, a guard-plate extending over the drum-opening, and a pivot-pin upon which the plate is mounted.

11. In a nail-distributor, the combination with a rotatable nail-drum having an opening, a nail-conveyor passing through the opening, a guard-plate extending over the drum-opening, a pivot-pin upon which the plate is mounted, and means for clamping

the pin in different lateral positions of the plate.

12. In a nail-distributor, the combination with a rotatable nail-drum having an opening, a nail-conveyor passing through the opening, a guard-plate extending over the drum-opening, a pivot-pin upon which the plate is mounted, a brace connecting the frame and guard-plate, and variable connections for the brace arranged to permit adjustment of the plate at the pivot-pin.

13. In a nail-distributor, the combination with a frame, of a nail-drum rotatable thereon and having an opening, a nail-way passing through the opening, a guard-plate for the opening, said guard-plate and the frame being formed with co-operating lugs in which are openings, and a bolt passing through the lug-openings and being of less diameter than one of these and threaded into the other lug.

14. In a nail-distributor, the combination with a frame, of a nail-drum rotatable thereon and having an opening, a nail-way passing through the opening, a guard-plate for the opening, said guard-plate and the frame being formed with co-operating lugs in which are openings, a bolt passing through the lug-openings and being of less diameter than one of these and threaded into the other lug, a brace connecting the guard-plate and frame, and slot-and-screw connections between the brace and the guard-plate and frame.

In testimony whereof I have signed my name to this specification.

THOMAS LUND.
